UNITED STATES PATENT OFFICE.

ROBERT C. MATTHES, OF WYOMING, NEW JERSEY, ASSIGNOR TO WESTERN ELECTRIC COMPANY, INCORPORATED, OF NEW YORK, N. Y., A CORPORATION OF NEW YORK.

ELECTRIC CIRCUITS.

Application filed January 15, 1920, Serial No. 351,605. Renewed February 20, 1924.

To all whom it may concern:

Be it known that I, ROBERT C. MATTHES, a citizen of the United States, residing at Wyoming, in the county of Essex and State 5 of New Jersey, have invented certain new and useful Improvements in Electric Circuits, of which the following is a full, clear, concise, and exact description.

This invention relates to electric circuits 10 and more particularly it relates to means for reducing the distortion in a repeating system.

An embodiment of the invention in which the effective input capacity of a vacuum 15 tube is made to serve as reactance of an end section of a filter has been chosen to illustrate the invention, the scope of the invention, however, being defined in the claims forming a part of this application.

20 As is well known in the art, weak currents or signals may be amplified to any desired degree by impressing them on one or more vacuum tube amplifiers arranged to work into each other by suitable circuit 25 connections. In employing a vacuum tube as an amplifier, it has been found that a tube works most efficiently if the impedance between the control electrode and the cathode is composed substantially of resistance with no capacity component. In 30 that form of the vacuum tube wherein the control electrode or grid is within the tube and adjacent the cathode there is present a certain amount of capacity between the 35 cathode and the grid dependent in value upon the size of the electrodes and the distance therebetween. This capacity effect is found to be appreciable even for currents of frequencies as low as 2,000 cycles or less and it has been found that the presence of this 40 capacity effect causes a certain amount of distortion in the current waves to be repeated by the tube. The general effect of this capacity is to produce a falling off in efficiency of the circuit at the upper part of 45 the frequency range to be transmitted, thereby serving as a limitation to the usefulness of the device.

It has furthermore been found convenient 50 in employing a vacuum tube as a repeater, to have associated with the repeater, a wave filter for limiting the range of frequency impressed on the tube from the incoming line. The general type of such a filter is shown, for example, in the Campbell

Patent No. 1,227,113 of May 22, 1917. As disclosed in this patent, a wave filter comprises inductance and capacity elements in series and in shunt with the line of such values as to prevent the undesired frequencies from passing therethrough, but offering little or no resistance to the passage of frequencies it is desired to impress on the repeater.

The calculation of the values of the impedance elements for each section of such a wave filter has hitherto been made without taking into account the capacity effect existing between the input electrodes of the amplifier. In accordance with this invention, however, the condenser employed in that section of the filter immediately preceding the repeater is changed so that the sum of the capacity of this condenser and the capacity of the tube is equal to the desired 60 capacity for that section of the filter. This change in the capacity element of the filter serves to neutralize the internal capacity of the tube for the frequencies of the current impressed thereon, thereby improving to a 65 considerable degree, the transmission characteristics of the repeater.

This invention will be better understood by reference to the following detailed description taken in connection with the drawings, in which Fig. 1 represents this invention in connection with a band wave filter and Fig. 2 represents the invention in connection with an ultra wave filter.

Referring now to Fig. 1 of the drawings, 70 4 is a vacuum tube repeater having a cathode 5, a control electrode 6 and an anode 7, which is adapted to impress on the outgoing line 8—8 amplified currents originating in source 9. Located between source 9 and tube 4 is a wave filter of a plurality of sections, consisting of inductances 10, 11 and 12, capacities 13, 14 and 15 in shunt to the line, and inductances 16 and 17 and capacities 18 and 19 in series with the line. 75 As described in the above mentioned Campbell patent, values may be assigned to these inductance and capacity elements such that the wave filter will readily transmit frequencies within a given range, but will suppress frequencies above and below the desired range. Preferably, inductance 12 should be equal to twice the value of inductance 11, that is, inductance 12 should be 80 equal to twice the value of the inductance 110

for the shunt circuit for a full section of the wave filter. Condenser 15 should be of such a value that, taken in connection with the effective capacity between the grid and cathode of tube 4, the combination of the two capacities is equal to one-half of the proper shunt capacity of a full section of the filter. This kind of a termination of a filter is usually called a mid-shunt termination. This mid-shunt termination is preferable since the impedance of the filter at mid-shunt approximates a pure resistance. In case, however, it is desired to terminate the filter at full-shunt section, inductance 12 should have the same value as inductance 11 and the sum of the grid capacity and capacity 15 should be equal to the capacity 14. By embodying the grid capacity as an element of the wave filter, the disturbing effect produced by the grid capacity is thereby eliminated. This modification of the wave filter will, therefore, improve to a considerable degree, the quality of the transmission between source 9 and the outgoing line 8. Resistance 25 which is connected between the grid and the cathode of tube 4 should be of a value equal to the impedance of the filter at its point of connection therewith, looking in the direction of the line.

Fig. 2 shows this invention in connection with a wave filter of a type which transmits frequencies below a desired value while suppressing frequencies thereabove. The filter is shown as consisting of capacities 27, 28 and 29, in shunt to the line and inductances 30 and 31 in series with the line. The sum of the capacity of condenser 29 and the capacity between the electrodes 5 and 6 of tube 4 should be equal to the value condenser 29 normally would have in the absence of repeater 4 for giving the filter the desired characteristic of transmitting certain frequencies while suppressing others. It is obvious that condenser 15 of Fig. 1 and condenser 29 of Fig. 2 may be omitted if the capacity between the electrodes 5 and 6 of the tube is equal to the capacity required in the last section of the filter. In practically every case it is possible to assign such values for the series elements of the wave filter that the proper value for the shunt capacity of the last section is equal to the grid capacity of the associated tube.

The sections of filter disclosed herein are similar in the sense that each section is made up of like reactances, coils and condensers similarly arranged. The corresponding reactances in successive sections may be equal, but the use of the word "similar" is not intended to imply that they are necessarily equal, for they may be graded along the filter from section to section.

What is claimed is:

1. In combination, a wave filter and an electrical discharge device associated there-

with, said device having an effective internal impedance comprising a resistance component and a reactance component, said wave filter having a plurality of impedances of such values with respect to each other 70 and to said reactance component as to cause said filter and said device to transmit certain desired frequencies while suppressing others, and one of said filter impedances having such a value as to effectively suppress said reactance component. 75

2. In combination, an electrical discharge device having an internal impedance comprising a resistance component and a reactance component, a wave filter of a plurality of sections comprising an incoming line, each of said sections comprising an impedance element in series with said line and an impedance element in shunt to said line, one of said sections having a reactance element dependent in value on said reactance component. 80

3. In combination, an electrical discharge device having an effective internal impedance comprising a resistance component and a capacity component, a line, a wave filter connected to said device and said line, said wave filter comprising a plurality of sections, each of said sections comprising impedance elements in shunt and in series 95 with said line of such values as to transmit certain frequencies while suppressing others, a shunt impedance in the section of said wave filter adjacent to said device having a value different from that required therefor to cause said last mentioned section to have the same electrical characteristics as the preceding section thereof whereby the effect of the capacity component of said device may be neutralized. 100

4. In combination, a line, an electrical discharge device having input and output electrodes, the impedance between said input electrodes comprising a resistance component and a capacity component, a wave filter between said line and said device comprising a plurality of sections each comprising an impedance element in series with the line and a condenser in shunt to the line, the condenser on the last section of said wave filter having a value less than the proper value for the capacity of said section by an amount equal to the capacity between said input electrodes. 110

5. In combination, a source of currents, a vacuum tube for amplifying currents of certain frequencies of said source, and means comprising impedance elements between said source and said tube for preventing undesired frequencies of said source from being impressed on said tube and for neutralizing the capacity component between the input electrodes of said device. 125

6. In combination, a source of currents, a vacuum tube for amplifying currents 130

- of certain frequencies of said source, and means comprising impedance elements between said source and said tube for preventing undesired frequencies of said source
- 5 from being impressed on said tube and for substantially neutralizing a reactance effect between the electrodes of said tube.
7. In combination, an electrical discharge device having an effective internal impedance comprising a resistance component and a reactance component, a line, a wave filter connected to said device and said line and comprising a plurality of sections, each of said sections comprising an impedance element in shunt to said line and an impedance element in series with said line of such values as to transmit certain frequencies while suppressing others, one of the impedances in that section of said wave
- 10 filter adjacent said device having a value different from that required therefor to cause said last mentioned section to have the same electrical characteristics as a preceding section thereof, whereby the effect
- 15 of the reactance component of said device may be substantially neutralized.
8. In combination, an electrical discharge device comprising a plurality of electrodes, a line, a localized electrical network connected to said device and said line, said network comprising a plurality of sections, each of said sections comprising an impedance element in shunt to said line and an impedance element in series with said
- 20 line, one of said impedance elements in each of a plurality of said sections having the same value, the corresponding impedance element in another of said sections having a value differing from the previous
- 25 mentioned value by an amount dependent upon an internal impedance characteristic of said device.
9. In combination, a transmission controlling circuit and a wave amplifying device associated therewith having an effective reactance facing said circuit, said circuit having a plurality of impedances of such values and arrangement with respect to each other and to said reactance that said
- 30 circuit and said device transmit with practically uniformly negligible attenuation currents of all frequencies of a range lying between an upper and a lower frequency limit, while attenuating and approximately extinguishing currents of neighboring frequencies, and one of said impedances having such a value as to effectively suppress said reactances.
- 35 10. In combination, an electrical discharge device having an internal reactance, a wave filter associated with said device and comprising impedances, said impedances being so constructed and arranged that said filter transmits an extended range of frequencies
- 40 while suppressing another extended range of frequencies, and one of said impedances being dependent in value upon said reactance.
11. In a selective circuit arrangement, a filter comprising a plurality of similar sections, each complete section consisting of lumped reactive series and shunt impedance elements, so proportioned that the filter structure will transmit with substantially equal attenuation a predetermined band of frequencies of a considerable range while substantially suppressing frequencies lying without the band, and a translating device associated with said filter, said translating device being so connected to the filter that the reactance of said device functions as at least a portion of one of the reactance elements of the filter.
12. In a selective circuit arrangement, a filter comprising a plurality of similar sections, each complete section consisting of lumped reactive series and shunt impedance elements so proportioned that the filter structure will transmit with substantially equal attenuation a predetermined band of frequencies of a considerable range, while substantially suppressing frequencies lying without the band, and a translating device associated with said filter, said translating device being so connected to the filter that the reactance of said device functions as one of said impedance elements of the last section of the filter.
13. In a selective circuit arrangement, a filter comprising a plurality of similar sections, each complete section consisting of lumped reactive series and shunt impedance elements so proportioned that the filter structure will transmit with equal attenuation a predetermined band of frequencies, while substantially suppressing frequencies lying without the band, and a translating device associated with said filter, said translating device being so connected to the filter that the effective capacity of said device functions as a capacity element of the filter.
14. In a selective circuit arrangement, a filter comprising a plurality of similar sections, each complete section consisting of lumped reactive series and shunt impedance elements so proportioned that the filter structure will transmit with equal attenuation a predetermined band of frequencies, while substantially suppressing frequencies lying without the band, and a translating device associated with said filter, said translating device being so connected to the filter that the effective capacity of said device functions as a capacity element of the last section of the filter.
15. In a selective circuit arrangement, a filter of the recurrent section type having a critical cut-off frequency, and transmitting without substantial attenuation currents of a considerable finite range of fre-

quencies on one side thereof, and substantially attenuating currents of frequencies on the other side of said critical frequency, in combination with a translating device connected to said filter and having a reactance facing said filter, said filter having a special section composed of impedance elements made up, in part, at least, of said reactance of said translating device.

10 16. In a selective circuit arrangement, a filter of the type having recurrent sections, and each section being composed of lumped impedance elements, and the filter as a whole

having a critical cut-off frequency range on one side thereof and substantial attenuation on the other side thereof, in combination with a terminal translating device having reactance components which are substituted, in part, at least, as the impedance elements of the proper end section of the filter to produce a minimum of reflection effects at the end of the filter.

In witness whereof, I hereunto subscribe my name, this 12th day of January, A. D. 1920.

ROBERT C. MATTHES.
